UNITED STATES PATENT OFFICE.

ARTHUR E. BARTER, OF ROSLINDALE, MASSACHUSETTS.

LOCKING DEVICE FOR PRINTERS' GALLEYS.

1,088,256.

Specification of Letters Patent.

Patented Feb. 24, 1914.

Application filed June 28, 1913. Serial No. 776,367.

To all whom it may concern:

Be it known that I, ARTHUR E. BARTER, a citizen of the United States, residing at Roslindale, in the county of Suffolk and State 5 of Massachusetts, have invented certain new and useful Improvements in Locking Devices for Printers' Galleys, of which the following is a specification, reference being had to the accompanying drawings, forming part 10 thereof.

This invention has reference to improvements in galley locks, so called, adapted for use in locking printing forms in printers' 15 galleys and particularly to improvements in such locking devices adapted for adjustment relative to the size of the printing form whereby a printing form of any size, within limits, can be readily locked in position in the galley.

One object of the invention is to so construct a locking device of this nature carrying all the mechanical elements or members necessary to its adjustment, positioning and locking in the printer's galley to secure the 25 printing form therein.

Other objects of the invention will appear from the following description.

The invention consists in the locking device herein shown and described.

Figure 1, represents a plan view of a printer's galley with a printing form placed therein and secured by the improved locking device. Fig. 2, represents a sectional view of the same taken on line 2—2 Fig. 1 looking in the direction indicated by the arrows. Fig. 3, represents an enlarged sectional view of the same taken on line 2—2 Fig. 1. Fig. 4, represents a plan view of the locking slide whereby the furniture bearing 30 against the end of the printing form may be held in place.

Similar characters of reference designate corresponding parts throughout.

In the art of printing it is usually desirable from time to time to take proofs of the printing form or matter set up in the galley so that corrections may be made to such matter, and, to this end, it is of course necessary that such printing matter, consisting 45 of individual type, linotype slugs or any other well known printing devices, should be so locked together that a proof can be taken.

The purpose of this invention is to provide a locking device adapted for such use

and capable of being readily adjusted to lock in position any size of printing form.

In the drawings *a* represents the usual and well known printer's galley having the upturned sides *b* and *c* and the upturned 60 end *d*.

T, *T* indicate the type or printing form and *f* a piece of printer's furniture adapted to form a wall against the end of the printing 65 form.

The improved locking device comprises the straight edge member 5 having the right angular extension or base member 6 which latter is furnished, preferably, with a pair of longitudinally extending slots 7, 7 having, at their ends adjacent the member 5, the racks 8, 8. Secured to the member 6 are the upstanding studs 9, 9 corresponding in number to the racks 8, 8, and on these studs 9, 9 are pivotally mounted the spacing arms 10, 10 which have pivots 11, 11 at their outer ends on which are pivotally mounted the complementary spacing arms 12, 12 which swing beneath said arms 10, 10 and have ends movable beneath the base member 6 70 which ends are furnished with the upstanding headed studs 13, 13 the shanks of which are engaged with and are proportioned to slide along slots 7, 7 between one edge of 75 said slot and the teeth of said racks 8, 8, while the shanks of said studs 13, 13 may be engaged with the teeth of said racks 8, 8. The heads of said studs 13, 13 prevent the disengagement of said studs from slots 7, 7. On the pivots 11, 11 are rotatably mounted 80 the helical cams 14, 14 which have the arms 15, 15 furnished with the finger or thumb plates 16, 16.

The straight edge member 5 is preferably of a length equal to that of galley *a* and said straight edge member forms a guide for the slide locking member 17 which extends at right angles to the general extension of said straight edge member 5 and preferably is struck up from a single piece of metal to form the upstanding walls 18, 18 and the bent tongue 19 having the punched out projection 20 extending in line with the bottom of this slide lock so that when the bent tongue 19 is slidably engaged over the edge 90 of member 5 said projection 20 extends partially beneath member 6 and prevents the upward movement of the locking member 17 to disengage the tongue 19 from member 5. Pivotally mounted on this tongue 19 100

and operating through an opening therein is the lever 21 the pivoted end of which has a helical cam shape 22 whereby, in one position of said lever, said cam end bears 5 against member 5 and frictionally locks said tongue 19 to said member.

The types or other printing elements T, T are first arranged in the galley and the straight edge member 5 of the improved 10 galley lock is placed against one edge of said combined types or printing elements, spacing arms 12, 12 are then moved toward arms 10, 10 until cams 14, 14 are approximately in contact with a wall of the galley, 15 said cams 14, 14 are then swung on their pivots and act against the galley wall with which they are in contact to crowd member 5 of the galley lock against the type. The strip of furniture f is now placed against 20 the end of the type matter and the slide locking member 17 is slid along on the straight edge 5 until one of the walls 18 of said member 17 bears against said furniture f when lever 21 is swung to locking 25 position. A proof of the type matter, thus locked, may now be taken after which the galley lock may be released, as to its pressure on the type, by the reverse swinging of the cams 14, 14 and any desired corrections 30 may be made or the galley lock may then be removed from the galley.

Having thus described my invention I claim as new and desire to secure by Letters Patent.

35 1. A galley lock of the nature described comprising a straight edge member having spacing members, helical locking cams pivotally mounted on said spacing members, and an end locking member slidably mounted on said straight edge member and having a locking means.

40 2. A galley lock of the nature described comprising a straight edge member having a laterally extending base member, a pair 45 of spacing arms of which one arm is pivotally connected with said base member,

and locking cams pivotally mounted at the junction of said spacing arms.

3. A galley lock of the nature described comprising a straight edge member having 50 a base furnished with a rack, a spacing arm pivotally mounted on said base, a second spacing arm pivotally connected with said first arm and having at its free end means for engaging said rack, and a helical cam 55 rotatably mounted on the pivot connecting said arms.

4. A galley lock of the nature described comprising a straight edge member having a lateral base member furnished with a longitudinal slot having a rack, a spacing arm pivotally mounted on said base member, a second spacing arm pivotally connected with said first arm and having at its free 60 end a stud slidable in the slot of said base 65 member and adapted to engage said rack, and a helical cam rotatable on the pivot connecting said arms.

5. A galley lock of the nature described comprising a straight edge member having 70 a lateral base member furnished with longitudinally extending slots having racks, arms pivotally mounted at the upper sides of said base member, spacing arms pivotally connected with said first mentioned arms 75 and having their free ends extending beneath said base member and provided with studs slidable in the slots of said base member and adapted to be engaged with the racks thereof, helical cams rotatable on the 80 pivots at the junctures of said pairs of arms, said cams having thumb pieces, and an end locking member slidable on said straight edge member and having a tongue engaged beneath said base member, and a locking lever pivotally mounted on said slidable member and adapted to frictionally engage said straight edge member. 85

ARTHUR E. BARTER.
